UNITED STATES PATENT OFFICE

JAMES M. KENDALL, OF SCOTIA, NEW YORK, ASSIGNOR TO GENERAL ELECTRIC COMPANY,
A CORPORATION OF NEW YORK

ELECTRICAL APPARATUS

Application filed June 1, 1927. Serial No. 195,792.

5 My invention relates to sound-reproducing apparatus, and has for its principal object the provision of an improved arrangement for obviating the disagreeable sound that is likely to occur in searching for a distant station when a radio-receiving apparatus adjusted for maximum sensitivity is tuned through a local transmitting station.

10 It is desirable that an apparatus utilized to prevent the disagreeable blast of sound produced by tuning a sensitive radio-receiving device through a loud local station be capable of limiting the input voltage of the receiver to a predetermined value and have no effect on the received impulses until this 15 value is attained. In accordance with my invention, this result is produced by means comprising a pair of unilaterally conductive or rectifying elements connected in shunt to the receiver input circuit and arranged to 20 transmit current only when the voltage of this circuit exceeds a predetermined value.

25 My invention will be better understood from the following description when considered in connection with the accompanying drawings and its scope will be pointed out in the appended claims.

30 Referring to the drawings, Fig. 1 is a wiring diagram of a receiving apparatus where- in my invention has been embodied, and Figs. 35 2 and 3 illustrate certain details in the operation of this apparatus.

This apparatus comprises a telephone device or loud speaker 1 which is provided with an operating winding 2 and a field winding 3. Current is supplied to the operating winding 2 from a supply circuit 4 through a transformer 5, a space-discharge device 6, and the field winding 3 which is interconnected with 40 a pair of condensers 7 and 8 to form a filter whereby fluctuations in the anode supply voltage of the device 6 are obviated. Connected in shunt to the anode circuit of the device 6 and transformer 5 is an impedance 45 device shown as a resistor 9 provided with

taps through which a negative bias potential is applied to the grid circuit of the device 6. The output current of the device 6 is modulated by potential impulses applied to an input transformer 11 through input leads 12 from a radio amplifying and detecting apparatus which may be energized by current supplied through the various taps of the resistor 9 or in any other suitable manner. In the present example, the secondary of transformer 11 is included in the grid circuit of device 6 whereby the leads 12 are connected with the grid circuit and voltage impulses are supplied to said grid circuit from the input leads 12. The detecting and amplifying part of the apparatus connected to the leads 12 has been omitted from the drawings to facilitate an understanding of the invention.

55 In order to limit the voltage between the input leads 12 to a predetermined value, they are arranged to be interconnected through means comprising a switch 13, a condenser 14, and a pair of carborundum crystals 15 and 16 which are interconnected through a section 17 of the resistor 9 to form a closed loop circuit. It should be understood that the condenser 14 is provided for excluding from the crystals 15 and 16 direct current which would otherwise tend to flow through the circuit 12, and that the crystals 15 and 16 are oppositely connected so that the overload current of the input circuit is transmitted between the leads 12 through one of the crystals in one direction and through the other crystal in the opposite direction.

60 The operating characteristics of the crystals 15 and 16 are illustrated by Figs. 2 and 3. As indicated by Fig. 3, there is a considerable voltage range within which no current is transmitted through the crystal. At one end of this range, however, the current transmitted through the crystal increases very rapidly while the voltage is maintained 65 substantially constant. The purpose of the 70 75 80 85 90 95

resistor section 17 is to provide a bias potential whereby the proper relation is maintained between the operation of the crystals 15 and 16. The effect of this bias potential is indicated by Fig. 2 wherein the voltampere characteristic of the crystal 15 is indicated by the curve *a*, that of the crystal 16 is indicated by the curve *b*, and the bias potential of the resistor section 17 is indicated by the horizontal distance *c* which extends substantially equal distances on either side of the origin 0.

The crystals 15 and 16 have no effect on the potential of the input transformer 11 so long as the input voltage applied to the circuit 12 is maintained within the limits determined by the bias voltage of the resistor section 17. When these limits are exceeded in either direction, however, current is transmitted through one or the other of the crystals and the input voltage of the device 6 is limited to a value which does not produce a disagreeable sound when a sensitive amplifying and detecting apparatus connected to the leads 12 is tuned through a strong local station in searching for a distant station. It will be apparent that the bias potential applied between the crystals 15 and 16 may be derived from any suitable source other than the resistor 9 and that the switch 13 need be closed only while tuning the apparatus to the frequency of the station which it is desired to receive.

What I claim as new and desire to secure by Letters Patent of the United States, is,—

35. 1. The combination of a space-discharge device provided with a grid circuit and input leads connected therewith, a direct current supply means connected to the output circuit of said device, and a pair of carborundum 40 crystals interconnected through said supply means and arranged to maintain the voltage between said input leads within predetermined limits.

45. 2. The combination of a space-discharge device provided with a grid circuit, and input leads connected therewith, a direct current source of potential, a pair of unilaterally conductive elements arranged to be interconnected with said source to form a closed loop 50 circuit therewith, each of said elements being oppositely connected in shunt to said input leads, and means for precluding the transmission of direct current between said source and said input circuit.

55. 3. The combination of a space-discharge device provided with grid and output circuits, input leads for said grid circuits, an impedance device connected between the terminals of said output circuit, and a pair of 60 unilaterally conductive elements interconnected through a section of said impedance device to form a closed loop connected in shunt to said input leads.

65. 4. The combination of a space-discharge device provided with grid and output cir-

cuits, input leads for said grid circuit, an impedance device connected between the terminals of said output circuit, a pair of unilaterally conductive elements interconnected through a section of said impedance device 70 to form a closed loop connected in shunt to said input leads, and connections whereby a part of the potential drop of said impedance device is applied to said grid circuit.

In witness whereof, I have hereunto set 75 my hand this 31st day of May, 1927.

JAMES M. KENDALL.
